METHOD OF IMPREGNATING WOOD

Joseph R. Coolidge, Brookline, and John H. McCready, Newton, Mass.; said McCready assignor to said Coolidge

Application May 11, 1932, Serial No. 610,721

3 Claims. (Cl. 21—12)

This invention relates to the impregnation of wood and articles made of wood, or similar materials which can be impregnated by essentially the same methods, for the purpose of preserving the wood, making it waterproof, or otherwise improving its characteristics and properties. While not limited thereto, the invention is especially concerned with the impregnation of wood with substances such as high melting point waxes and waxy compounds which are hard and non-tacky under ordinary temperature conditions but which can be forced into the pores and tracheids of the wood under pressure while the impregnating substance is in a melted condition. For example, impregnations with Montan wax and with creosote mixed with Montan wax are now used to a substantial extent in treating wood to preserve it, increase its resistance to water, and to improve its characteristics in other respects. The present invention is especially concerned with the apparatus and methods of producing impregnations with materials of this general character.

As is well understood by those skilled in the art of wood impregnation, processes of this character which require the use of pressure to force the impregnating material into the inner strata of the wood, must be performed in a pressure cylinder. According to the usual commercial practice the wood is loaded on trams which are run into the cylinder on a track and which remain in the cylinder during the impregnating operation. Usually the cylinders are very large, are heavily constructed, and they must be closed tightly during the entire pressure period. After the treatment has been completed the impregnating material is withdrawn from the cylinder, the cylinder is opened, the trams are run out into the open air, and the impregnated pieces are allowed to cool. Since impregnating materials of the type which are solid at normal temperatures set or harden rather quickly, and since there is usually a surplus of this material on the outer surfaces of the impregnated pieces, it is customary to run these pieces through a cleaning operation for the purpose of removing this excess of material.

This method can be and is used very satisfactorily in the treatment of sizable pieces of wood. It is not practical, however, to impregnate some articles by this process. For example, shingles, clapboards, and certain kinds of flooring, present peculiar problems because of the fact that they are individually small and are commonly handled in bunches. If, for example,

shingles or clapboards were to be treated in the manner above described, it would be necessary to break open the bunches at the conclusion of the process and to clean the individual shingles or clapboards, since otherwise the whole bunch would be solidified into a solid mass by the cooling and setting of the impregnating medium. Obviously, also, such pieces could not, as a practical matter, be handled in bulk in a pressure cylinder for similar reasons. In other words, while the impregnations can be made in this manner, the labor cost involved in them is so high, because of the nature of these articles, that it is not practical to impregnate them at the present time. In fact, no process or apparatus is available at the present time, so far as we have been able to learn, with which pressure impregnations of shingles, clapboards, and other articles of a similar nature can be made on any price basis which gives even a hope of being practical.

A careful consideration of the problem and the various factors involved in it leads to the conclusion that articles of this kind must be handled on some kind of a conveyor system so that the process can be made substantially continuous. This conclusion, however, is of little assistance when considered in connection with the fact that pressure impregnations must be performed in a closed cylinder where both the material to be impregnated and the treating liquid can be confined and the desired pressure imposed on them.

The present invention deals especially with the problem presented by these conditions. It aims to devise both a thoroughly practical process and an apparatus with which it may be practiced for making pressure impregnations of shingles, clapboards and other small wooden parts and articles of a similar nature at a cost which will make it entirely feasible to impregnate these articles on a commercial basis.

The nature of the invention will be readily understood from the following description when read in connection with the accompanying drawings, and the novel features will be particularly pointed out in the appended claims.

In the drawings,—

Figure 1 is a perspective view of an apparatus constructed in accordance with this invention;

Fig. 2 is a side view of the apparatus shown in Fig. 1, the view being broken to indicate that it is much shortened in height;

Fig. 3 is a diagrammatic view, partly in section, of the same apparatus, this view also being

broken to indicate that no attempt has been made to indicate proportions;

Fig. 4 is a plan view showing certain details of the conveyor;

5 Fig. 5 is a side elevation of a portion of the conveyor; and

Fig. 6 is a sectional view approximately on the line 6—6, Fig. 4.

In impregnating shingles, clapboards, hard 10 wood flooring, and the like, substantial pressures are required, such pressures running from, say, twenty-five pounds to the square inch to one hundred pounds, or even more. In addition, it is extremely desirable, as above indicated, that 15 any method for impregnating articles of this character should be continuous. We have found that both of these objects can be realized, while still maintaining the expense of the treating plant within reasonable limits, by using an open ended 20 treating cylinder arranged vertically, making it of such a height as to give the desired working pressure, and handling the pieces to be treated on a continuous conveyor, the use of an open ended cylinder making it possible to employ a 25 conveyor. The hydrostatic pressure of impregnating materials of the character above mentioned is in the neighborhood of .45 of a pound per foot of head. Consequently, if the pieces which are to be treated will require a treating 30 pressure of fifty pounds per square inch, a vertical or inclined cylinder having a height of approximately one hundred and twenty feet would be required. Practical considerations very likely 35 would also make it advisable to build the cylinder considerably in excess of this height so that a higher pressure would be available.

Figs 1, 2 and 3 show a cylinder constructed in accordance with this invention, it being understood that the term "cylinder" is here used not 40 at all in its geometrical sense but rather in the functional sense in which it is employed in this industry to designate the container in which the impregnating liquid is confined and is placed under the desired pressure necessary to force it 45 into the wood. In the particular arrangement shown the cylinder is given an approximately U-shaped form and is set on end. For convenience in installation advantage may be taken of an abrupt hillside, cliff, or the like, if such is available, 50 so that the expense of building a tower or other supporting structure will be eliminated, or at least greatly reduced. The particular cylinder structure shown has two very tall upwardly extending legs 2 and 3, joined at their lower ends 55 by a larger horizontal section 4.

A conveyor, indicated diagrammatically at 5 in Fig. 3, is installed in the cylinder and is driven from an electric motor 6 through suitable reduction gearing. The conveyor chain runs on suitable 60 driving and guiding sprocket wheels 7, the number of such wheels used necessarily depending upon the requirements of individual installations. Preferably the motor 6 is of the variable speed type so that the rate of travel of the conveyor chain 5 can be adjusted and controlled 65 within reasonable limits.

It will be observed that the conveyor includes an upper horizontal reach or run extending across a suitable platform 8. It also includes a series 70 of grippers 10, Figs. 4, 5 and 6, or equivalent devices for holding the shingles or other articles to be impregnated. In the particular construction shown in the drawings the grippers 10 are carried by certain of the conveyor links, and each 75 gripper includes a lower fixed jaw a, Fig. 6, and

an upper movable jaw b pivoted to the lower jaw at c, the upper jaw also having a lower arm or extension d which underlies the lower jaw a and is pressed away from it by a coiled spring e. Normally the spring holds the gripper closed and therefore enables the gripper to hold a shingle S securely in it. As the conveyor travels across the platform 8 the arm d is engaged by the beveled edge of a stationary cam plate 12, Figs. 3 and 5, which swings this arm upwardly and thereby 10 opens the gripper. The gripper is held in this open condition during the entire period in which it is moving across the plate 12, and during this interval, therefore, a workman may place a shingle, clapboard, or other article to be impregnated, between the jaws of the gripper, holding it in this position while the gripper slides off the right-hand end, Fig. 3, of the cam plate and closes on the article, thus gripping it securely. This operation is repeated as successive grippers 20 move across the plate 12. The conveyor carries these articles successively down the right-hand leg 2 of the cylinder and along the lower horizontal run of the conveyor which is located in the cylinder section 4, and then carries them up the 25 other leg of the cylinder and across the cam plate 12 again. On the way to the cam plate each gripper carries its shingle between a pair of revolving brushes 14—14, Fig. 3, which serve to remove excessive impregnating material from 30 the surface of the shingle, this action being facilitated by the fact that the gripper engages the shingle at one edge and preferably near the thinner end so as to leave most of the body of the shingle fully exposed for the action thereon of 35 the brushes. A moment later the gripper is opened by its contact with the leading edge of the cam plate 12, whereupon the shingle is released and drops by gravity into an inclined chute 15 which carries it to the bunching machine, or to 40 any other desired point of delivery. Obviously the shingles to be impregnated may be carried up to the platform 8 by a conveyor, or they may be delivered to the workmen in any other convenient manner.

It will be observed that as the shingles are carried down the long leg 2, Fig. 1, of the cylinder to the lower horizontal section 4, the pressure on the portion of the impregnating liquid through which the shingle passes successively, 50 gradually is increased until it reaches a maximum when the shingle arrives in the section 4. It is maintained under this maximum pressure for a length of time determined by the length of this lower horizontal run of the conveyor and 55 by the conveyor speed. For this reason it is very desirable to be able to control and adjust the conveyor speed, as above described. Small or thin articles of wood, such as shingles, clapboards, and the like, do not, as a rule, require 60 a long treating period in order to produce a penetration of the treating liquid into the wood for a substantial depth. In thin pieces, like shingles, a through and through impregnation is preferable, and this may also be desirable in 65 certain grades of flooring, clapboards, and the like. However, this is not always necessary, and for many purposes a penetration of in the neighborhood of an eighth of an inch is quite sufficient. It should be understood, however, that the 70 degree of penetration obtained will depend upon the species of the wood, its condition as to moisture content, the length of the treating period, the pressure employed, the nature of the impregnating liquid, the temperature at which the im- 75

pregnating bath is maintained, and other practical considerations well understood by those skilled in the art of wood impregnation.

In making impregnations with Montan wax, creosote, and the like, it is desirable to maintain the treating bath at a temperature of between 220° and 250° F. Consequently, provision must be made for heating the bath in the cylinder. For this purpose a series of steam pipes 16 are located in the cylinder section 4, and additional steam pipes are located in the cylinder legs 2 and 3, or these legs may be steam jacketed as shown at 17, Fig. 3. Steam for this purpose is supplied from the boiler house 18, Fig. 1. It is also expected that the cylinder will be properly insulated to hold the heat radiation within reasonable limits.

The mixing and supply tanks required in connection with the cylinder, together with suitable pumps for forcing the impregnating liquid into the cylinder and controlling its height or hydrostatic head, may be substantially the same as those used with pressure cylinders of the common commercial types, it being understood that sound engineering principles and good treating plant practice should be followed in making any installation embodying this invention.

It will be evident from the foregoing that small articles, such as shingles, clapboards, and the like, can be handled very economically and efficiently in this plant, that in it they can be given a pressure impregnating treatment just as effectually as in a pressure cylinder of the present commercial types in which the loads or charges must always be handled on a batch system. The invention, therefore, makes it feasible for the first time, so far as we are aware, to impregnate shingles, clapboards, hard wood flooring, and other small articles of wood on a commercial basis.

While we have herein shown and described a typical embodiment of our invention and a preferred method of procedure, it will be understood that the invention may be embodied in other forms, and that the steps of the process may be varied in some respects without departing from the spirit or scope of the invention. For example, the treating cylinder may take a great variety of forms, and the particular design used in any given installation will necessarily vary with the practical requirements of the individual

location. It is contemplated that the invention will be found useful in the impregnation of mine props and other mine timber which is used in short lengths, and that where so used the cylinder may take the form of a single upright section which may be conveniently located in an abandoned mine shaft, the conveyor running through the cylinder just as it does in the arrangement here illustrated, but having very short horizontal runs.

Having thus described our invention, what we desire to claim as new is:

1. That improvement in methods of pressure impregnating articles of wood, and the like, which consists in passing said articles successively through a liquid impregnating bath in which a high pressure is maintained, holding said high pressure on a portion of said bath by maintaining a hydrostatic column of liquid in communication with said high pressure portion, and conveying said articles through said column.

2. That improvement in methods of pressure impregnating articles of wood, and the like, which consists in passing said articles successively through a liquid impregnating bath in which a high pressure is maintained, maintaining a column of liquid in communication at its lower end with said high pressure portion of said bath but open to the atmosphere at its upper end and thereby imposing a high hydrostatic pressure on said portion of the bath, and conveying said articles through said column.

3. That improvement in methods of pressure impregnating articles of wood, and the like, which consists in conveying said articles successively through a liquid impregnating bath which is kept under high pressure, maintaining two columns of liquid each in communication at its lower end with the high pressure portion of the bath and both open to the atmosphere at their upper ends, whereby a high hydrostatic pressure is maintained on said high pressure portion of the bath, and moving said articles downwardly through one of said columns into said high pressure portion, through said portion of the bath, and upwardly out of said bath through the other column to the atmosphere.

JOSEPH R. COOLIDGE.

JOHN H. McCREADY.
